SAFETY CONTROL AND IGNITION SYSTEM
FOR GASEOUS FUEL BURNERSCharles K. Strobel, Pittsburgh, Pa., assignor to
Robertshaw-Fulton Controls Company, Young-
wood, Pa., a corporation of Delaware

Application October 11, 1947, Serial No. 779,338

5 Claims. (Cl. 158—117.1)

1

This invention relates to safety control and ignition systems for gaseous fuel burners and, more particularly, to electrical systems therefor.

In apparatus of this general character the flow of fuel to the main burner may be controlled by an electromagnetic control device which is energized by the current generated by a thermocouple or thermopile responsive to the heat of a flame at the pilot burner. Means are employed for placing the armature of the electromagnet in attracted position and the fuel control device in a flow permitting position, such operation being generally termed "resetting." The means employed for resetting may be electrically operated from a source of current separate from that generated by the thermocouple. It is apparent that once the resetting operation is completed the current from this separate source is no longer required and the system may be left under the sole control of the thermoelectric current which is generated as long as the pilot burner produces a flame.

As disclosed in my copending application, Serial No. 580,672, filed March 2, 1945, now Patent No. 2,454,848, dated November 30, 1948, a timing device is used in such construction for automatically disconnecting the system from the external current supply upon completion of the resetting operation. The manual operation of the fuel control valve or thermostat to initiate the starting period may also serve to operate the timing switch. However, such manual operation of a timing switch, particularly of the mercury-type, may introduce undesirable features into the arrangement. Consequently, an object of this invention is to render the operation of such a timing device entirely automatic in a system of the kind described.

Another object of the invention is to reset an electromagnetic device by electrically operated means which are automatically rendered inoperative upon completion of the resetting operation.

Another object of the invention is to energize an electric igniter for the pilot burner from the same source of current as is used for energizing the resetting means.

Another object of the invention is to associate various elements of the control system in compact units requiring a minimum number of operations to place the system in running condition.

Other objects and advantages will become apparent from the following description taken in connection with the accompanying drawing

2

wherein is shown a schematic embodiment of the safety control and ignition system of this invention in conjunction with the main and pilot burners of a gaseous fuel burning apparatus.

Referring more particularly to the drawing, a main burner 10 is supplied with fuel by a main fuel pipe 12 and the flow of fuel therein is under the separate control of a main control device, shown as a valve 14, and of a safety valve 16. The main valve 14 is manually operable by a handle 18 between the open and closed positions indicated by the legends "On" and "Off," respectively. A conduit 20 for supplying fuel from the main fuel pipe 12 to a pilot burner 22 is connected to the main valve 14 to receive a supply of fuel when the main valve 14 is in the "On" position. The main burner 10 and pilot burner 22 form the fuel burning apparatus to which the safety control system is applied.

The safety valve 16 is an electromagnetic control means for the fuel flow in pipe 12 and is located between the main valve 14 and the main burner 10. This valve 16 is provided with a partition 24 between the inlet and outlet openings and has a valve seat 25 with an opening 26 therethrough controlled by a reciprocable valve member 28. A valve stem 30 for the valve member 28 projects exteriorly of the safety valve 16 and carries a coil spring 32 serving to bias the valve member 28 toward the valve seat 25. An armature member 34 is carried on the exterior end of the valve stem 30 for cooperation with a horseshoe magnet 36. When the valve member 28 is in the open position shown in the drawing, the armature 34 is in its attracted position against the pole faces of the magnet 36. A suitable coil or winding 38 is provided for the magnet 36 and connected by wires 42 and 44 in circuit with a thermocouple 40.

The thermocouple 40 is located in proximity to the flame of the pilot burner 22 and is adapted to be heated thereby. As is known to those skilled in the art, the thermocouple 40 is a device capable of generating sufficient electrical energy when heated to retain the armature 34 against the pole faces of the magnet 36 but is incapable of actuating the armature 34 to this position. Accordingly, the safety valve 16 is provided with electromagnetic reset means now to be described. A reset stem 46 projects into the interior of the safety valve 16 on the side of the partition 24 opposite the valve member 28 and is biased to an inoperative position outwardly of the safety valve 16 by a coil spring 48. The reset stem 46 and

valve stem 30 are preferably in axial alignment and extend in opposite directions from the valve seat opening 26 which is axially aligned therewith.

The reset stem 46 carries a closure member 50 for the valve seat opening 26 and forming a flow interrupter for the safety valve 16. Formed on the reset stem 46 beyond the closure member 50 is a stem projection 52 which is engageable with a stem projection 54 formed on the valve stem 30 beyond the valve member 28. When the reset stem 46 is moved inwardly toward the valve seat 25 with the valve member 28 seated thereon, the engagement of the projections 52 and 54 will serve to force the valve member 28 away from the valve seat 25 and position the armature 34 in engagement with the pole faces of the magnet 36. At the same time, the closure member 50 will overlie the valve seat opening 26 thus preventing flow of fuel through the main fuel pipe 12 to the main burner 10. It will be observed that fuel may flow in the conduit 20 to the pilot burner 22 during the period that the main burner flow is thus interrupted. It will be apparent, however, that the closure member 50 could be dispensed with and the resetting operation just described could be conducted while fuel flows simultaneously into the main fuel pipe 12 and pilot conduit 20.

The reset stem 46 is adapted to be moved inwardly against the bias of the spring 48 by the electromagnetic portion of the resetting means now to be described. This means comprises a transformer 56 combined with an electromagnetically operated plunger 58 which is reciprocable on an axis substantially parallel to the axis of the reset stem 46. A primary coil 60 of the transformer 56 serves to energize the electromagnet and attract the plunger 58 causing movement thereof from the full line position shown in the drawing to the broken line position also shown therein. The transformer 56 has a secondary coil 62 connected in circuit with an electric igniter 63 for the pilot burner 22 by means of wires 65 and 67. It will be apparent that the safety valve 16 and associated operating magnet 36, together with the transformer 56, could be combined in a unitary construction and that these elements have been shown schematically in the drawing for illustrative purposes without intending any limitation to the exact form shown.

The plunger 58 of the transformer 56 carries an operating arm 64 for an initially closed time-switch means 66 in the form of a mercury switch adapted to be tilted to open position when the plunger 58 is in the broken line position. The time-switch means 66 is adapted to assume an open position only after the expiration of a predetermined period following operation thereof such as by providing a restricted exit for the mercury from one end of the tube to the other. In such devices an instantaneous reset characteristic is provided by an unrestricted inlet for the mercury flow back to its initial location. The usual electrodes 68, 70 are associated with the time-switch means 66 and cooperate with the mercury therein to close a circuit when the plunger 58 is in the full line position shown in the drawing. The operating arm 64 carries a connection in the form of a lateral bar 72 pivoted intermediate its ends, one of which overlies the reset stem 46 for moving the same downwardly against the bias of the coil spring 48 when the plunger 58 is moved to the broken line position shown in the drawing.

This invention is more particularly directed to

an arrangement for actuating the time-switch means 66 automatically when the main fuel valve 14 is operated from "Off" to "On" position. Accordingly, a first initially open switch means 74 is provided and takes the form of a fixed contact 76 suitably mounted on insulation on the transformer 56 and adapted to cooperate with a relatively movable contact 78 suitably mounted on insulation on the plunger 58. Cooperable with the first switch means 74 is a second initially open switch means 80 in the form of a conventional push-button switch having a fixed contact 82 and a relatively movable contact 84 mounted upon a flexible switch arm 86 biased to a position for separating the contacts 82, 84. The flexible switch arm 86 extends into operative engagement with a lug 88 carried on the handle 18 of the main valve 14 opposite the indicia "Off" thereon. The arrangement is such that upon rotation of the handle 18 from the "Off" to the "On" position the lug 88 will operatively engage the flexible switch arm 86 and cause engagement between the contacts 84, 82. This engagement is temporary only due to subsequent movement of the lug 88 past the flexible switch arm 86 in reaching the "On" position, whereupon the contacts 82, 84 become disengaged.

The system is shown in the normal running position with both the main burner 10 and the pilot burner 22 producing a flame and the main valve 14 in the "On" position. When the valve 14 is in the "Off" position, the second switch means 80 is open as is the first switch means 74. The plunger 58 is in the released position shown in the drawing and the time-switch means 66 is in closed position as shown in the drawing with the mercury bridging the electrodes 68, 70. In order to bring the system into the normal running operation described, the handle 18 of the main valve 14 is rotated counter-clockwise from the "Off" toward the "On" position shown in the drawing. During this movement the lug 88 engages the flexible switch arm 86 and momentarily closes the contacts 82, 84. A circuit is thus established as follows: line wire 90, wire 92, primary coil 60, wire 94, contact 76, wire 96, contacts 82, 84, switch arm 86, wire 98, electrodes 70, 68, and wire 100 to line wire 102.

As will be apparent, this circuit places the primary coil 60 of the transformer 56, the contacts 82, 84 of the second switch means 80 and the electrodes 68, 70 of the time-switch means 66 in series with the source of electrical energy from line wires 90 and 102. It will also be apparent that the portion of the circuit from contact 76, line wire 96, contacts 82, 84 and switch arm 86, is in parallel with or serves to short-circuit the first switch means 74 which has its contacts 76, 78 open in this initial or starting position.

The transformer 56 being energized in the foregoing circuit, the igniter 63 becomes energized through its described connection with the secondary 62. Moreover, the plunger 58 is moved from the released position shown in the drawing to the attracted or broken line position, whereupon the contacts 76, 78 of the switch means 74 become closed and the time switch means 66 becomes tilted for unbridging the electrodes 68, 70 after a predetermined delay.

When the rotation of the handle 18 is completed and the main valve 14 reaches the "On" position, then the lug 88 has moved past the flexible switch arm 86 whereupon disengagement of the contacts 82, 84 of the switch means 80 under bias of the flexible switch arm 86 has occurred. However, the series circuit just traced remains closed

but through the first switch means 74 due to the described closing of the contacts 76, 78 thereof, it being noted that the electrodes 68, 70 are not yet unbridged by the mercury content of the time switch means 66. The operation of the plunger 58 to the broken line or attracted position has also served to rotate the pivoted bar 72 clockwise and thereby depress the end of the bar 72 which overlies the reset stem 46. The reset operation is now completed as the bias of the spring 48 is overcome. The closure member 50 thereupon operatively engages the partition 24 to close the opening 26 while the valve member 28 is moved to its open position. Moreover, the armature 34 is seated against the pole faces of the magnet 36. Thus, although the flow of fuel to the main burner 12 is cut-off, the pilot burner 22 receives fuel by way of conduit 20 and this fuel is ignited by the igniter 63 which is energized from the secondary 62 of the transformer 56.

At the end of the time-delay period of the switching means 66, which may be eighteen seconds from the initial turning on of the main valve 14, the electrodes 68, 70 become unbridged by the mercury and the circuit previously traced is opened. The deenergization of the primary winding 60 of the transformer 56 causes release of the plunger 58 and opening of the contacts 76, 78 of the switch means 74. While such release of the plunger 58 causes the time-switch means 66 to resume the tilted position as shown in the drawing, the bridging of the electrodes 68, 70 by the mercury does not cause a reestablishment of the circuit previously traced due to the contacts 76, 78 of the switch means 74 being concurrently opened. The igniter 63 is also deenergized and remains deenergized for the duration of the running operation which now ensues. The reset stem 46 is moved axially under bias of the coil spring 48 and the closure member 50 no longer closes off the opening 26 in the partition 24.

However, the valve member 28 remains in the open position and the armature 34 in its attracted position relative to the pole faces of the magnet 36 provided the thermocouple 40 is sufficiently heated by the flame at the pilot burner 22. Such heating of the thermocouple 40 serves to generate current to energize the coil 38 of the magnet 36 as long as the pilot burner flame remains burning. The system is thus set in the steady-state or running operation with the parts as shown in the drawing.

In the event that the flame of the pilot burner 22 is extinguished, then the thermocouple 40 ceases to generate current and the coil 38 becomes deenergized releasing the armature 34 and closing the safety valve 16 by movement of the valve member 28 into engagement with its seat 25. As such movement of the valve member 28 controls only the flow of fuel to the main burner 10, the flow of fuel through the pilot conduit 20 continues. The system is restarted by rotating the handle 18 to the "Off" position and then back to the "On" position as illustrated in the drawing. The system is thus of the non-recycling type and the only fuel which escapes unburned in the event of a safety shut-off is that which flows to the pilot burner. It will be understood, however, that the system could be arranged for 100 per cent shut-off of fuel by connecting the conduit 20 to a chamber provided between the valve member 28 and the closure member 50 as disclosed in Patent No. 2,391,753. It should be observed that the system requires no power for steady-state

operation and is therefore independent of voltage variations in power supply.

It is within the scope of the invention to dispense with the pilot burner component of the fuel burning apparatus and the flow interrupter of the safety valve assembly. In such event the thermoelectric means would be exposed to the heat of the flame at the main burner component which would be ignited directly by the electric ignition device. These and many other changes may be made in the details of construction, and arrangement of parts without departing from the scope of the invention so that this description and accompanying drawings are intended by way of illustration only and are not to be construed in a limiting sense.

I claim:

1. A control system for fuel burner apparatus having a source of electric energy, comprising electromagnetic control means biased to a fuel flow preventing position; electromagnetic reset means biased to an inoperative position and operable when energized for actuating said control means to a fuel flow permitting position, initially closed switch means adapted for controlling said reset means, a timing device operatively associated with said switch means for delaying operation thereof to an open position until expiration of a predetermined period following energization of said reset means and being substantially instantaneously reset for such operation upon deenergization of said reset means, initially open switch means for controlling said reset means and adapted when closed to establish a circuit including said reset means and said initially closed switch means, thermoelectric means connected to said control means and adapted to be located to be heated sufficiently by burning fuel at the burner during said period for energizing said control means and maintaining the same in said fuel flow permitting position, and means operable for establishing a temporary circuit for said reset means to close said initially open switch means and establish the first said circuit.
2. A control system for fuel burner apparatus having a source of electric energy, comprising electromagnetic control means biased to a fuel flow preventing position; electromagnetic reset means biased to an inoperative position and operable when energized for actuating said control means to a fuel flow permitting position, initially closed switch means adapted for controlling said reset means, a timing device operatively associated with said switch means for delaying operation thereof to an open position until expiration of a predetermined period following energization of said reset means and being substantially instantaneously reset for such operation upon deenergization of said reset means, initially open switch means for controlling said reset means and adapted when closed to establish a circuit including said reset means and said initially closed switch means, thermoelectric means connected to said control means and adapted to be located to be heated sufficiently by burning fuel at the burner during said period for energizing said control means and maintaining the same in said fuel flow permitting position, a second initially open switch means controlling a circuit in parallel with the first said initially open switch means, and means operable for closing said second initially open switch means momentarily to establish said parallel circuit and causing said reset means to close said first initially open switch means and establish the first said circuit.

3. A control system for fuel burner apparatus having a source of electric energy, comprising electromagnetic control means biased to a fuel flow preventing position; electromagnetic reset means biased to an inoperative position and operable when energized for actuating said control means to a fuel flow permitting position, initially closed switch means adapted for controlling said reset means, a timing device operatively associated with said switch means for delaying operation thereof to an open position until expiration of a predetermined period following energization of said reset means and being substantially instantaneously reset for such operation upon deenergization of said reset means, initially open switch means for controlling said reset means and adapted when closed to establish a circuit including said reset means and said initially closed switch means, thermoelectric means connected to said control means and adapted to be located to be heated sufficiently by burning fuel at the burner during said period for energizing said control means and maintaining the same in said fuel flow permitting position, a second initially open switch means controlling a circuit in parallel with the first said initially open switch means, manually operable means for controlling the flow of fuel to said control means, and means operatively associated with said manually operable means for closing said second initially open switch means momentarily to establish said parallel circuit and causing said reset means to close said first initially open switch means and establish the first said circuit.

4. A control system for fuel burner apparatus having a source of electric energy, comprising electromagnetic control means biased to a fuel flow preventing position, electromagnetic reset means having a coil and plunger operable thereby and biased to an inoperative position, means for mechanically connecting said plunger and said control means for actuation of the latter to a fuel flow permitting position when said coil is energized, initially closed time switch means mechanically connected to said plunger for operation thereby to assume an open position upon expiration of a predetermined period following energization of said coil, initially open switch means operable by said plunger to closed position upon energization of said coil and being adapted to establish a circuit for said coil and said time switch means, thermoelectric means electrically connected to said control means and adapted to be located to be heated sufficiently by burning fuel at the burner during said period for energizing said con-

trol means and maintaining the same in said fuel flow permitting position, and means operable for establishing a temporary circuit for said coil to cause said initially open switch means to close and establish the first said circuit.

5. A control system for fuel burner apparatus having a source of electric energy, comprising a fuel control valve biased to a closed position, electromagnetic means including a coil and an armature connected to said valve and operable

for holding the same in open position upon sufficient energization of said coil, a reset stem for actuating said valve to open position and being biased to an inoperative position, electromagnetic means having a winding and a plunger operable thereby between attracted and released positions, means for connecting said plunger to said reset stem for opening said valve upon operation of said plunger to said attracted position, initially closed time switch means operable by said plunger upon operation thereof to said attracted position, said time switch means being adapted to assume an open position upon expiration of a predetermined period following said plunger operation, initially open switch means operable by said plunger to closed position upon operation thereof to said attracted position, said initially open switch means being adapted to establish a circuit in said closed position including said

winding and said time switch means, thermoelectric means electrically connected to said coil and located to be heated sufficiently by burning fuel at the burner during said period for energizing said coil and maintaining said valve in open position, a second initially open switch means controlling a circuit in parallel with the first said initially open switch means, manually operable means for controlling the flow of fuel to said valve, and means operatively associated with said manually operable means for closing said second initially open switch means momentarily to establish said parallel circuit and causing said plunger to close said first initially open switch means and establish the first said circuit.
